CLAIM

The ornamental design for a bottle adapter, as shown and described.

DESCRIPTION

FIG. 1 is a front and top perspective view of a bottle adapter, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is another perspective view thereof, shown in a position of use with an exemplary bottle.

The broken lines are shown for the purpose of illustrating both parts of the article as well as environmental subject matter of an exemplary bottle. None of the broken lines form part of the claimed design.
